FRANK M. LEWIS, OF BRIGHTON, ENGLAND, ASSIGNOR TO GENERAL ELECTRIC COMPANY,
A CORPORATION OF NEW YORK.

ELECTRIC-ARC LAMP.

No. 894,168.

Specification of Letters Patent.

Patented July 21, 1908.

Application filed November 21, 1904. Serial No. 233,628.

To all whom it may concern:

Be it known that I, FRANK MICHAEL LEWIS, a subject of the King of Great Britain, and resident of Prestonville Terrace, Brighton, 5 England, have invented certain new and useful Improvements in Electric-Arc Lamps, of which the following is a specification.

The object of my invention is to use, in series with each other, more especially in a series circuit tapped across constant potential mains, an electric arc lamp, preferably of the inclosed type, which I have especially devised for that purpose, which lamp dispenses with the shunt-regulating coil and its attending expense and inconvenience and in which lamp therefore the entire arc-regulation is effected by a series regulating coil only.

In the ordinary lamp, of the inclosed arc type, which is actuated by a series coil and clutch, the feeding takes place in the first two hours or so after starting up the lamp by the travel of the core in the solenoid. Now assume that such a lamp were used in a series circuit tapped across parallel mains, that is 20 in a series circuit having an approximately constant potential impressed upon its terminals. As the carbons burn away and the arc lengthens, the current is momentarily diminished and the core moves down in its solenoid. This allows the upper carbon to move toward the lower carbon and thus restores the arc to about the same length and also restores the current to normal. Now usually 25 electric lamps having series regulating coils are designed so that their cores will work at the position of maximum pull for a given current in the solenoid. But the position of maximum pull on the core is also the position around about which there is a minimum variation of pull for a given current for different 30 positions of the core. It follows then, under our assumption, that practically the same current is required to hold each core in position, no matter what that position, between the extremes of its travel, may be. This, on 35 the one hand, would seem to be a desirable result, for it would seem to insure having at all times the same current flowing in the series circuit, no matter what the positions of the cores in the solenoids. But a closer analysis shows that it is impossible to run such lamps in series on a constant potential circuit and for this reason: If two or more such lamps be started, the arcs will naturally, by

accident if not otherwise, begin by being of unequal length. Such a condition being once established, there is no adequate restoring force tending to shorten the unduly long arc or to lengthen the unduly short arc. It is true, of course, that the position of the core in the lamp having the shorter arc differs from that of the core in the lamp having the longer arc. But since as shown above, practically the same amount of current is required to hold each of these cores in their different positions, these cores will remain in equilibrium in these positions and there will be no adequate force brought into play tending to have, as it were, a differential action to throw the two cores into the same relative position. Having started with different relative positions, the cores will continue in different relative positions, with corresponding different arc lengths, for the rest of their travel in the solenoid.

To make it possible to run an arc lamp, with a series regulating coil only, in series with other like lamps on an approximately constant potential circuit, I, in accordance with my invention, so construct the lamp 80 that the armature of the regulating magnet shall not, in its travel, be in equilibrium in its different positions for the same current. On the contrary I have so constructed it that for every different position of the armature 85 there corresponds a different current strength to hold the armature in equilibrium. Put more specifically, I so design the lamp that the pull of the armature which has to be balanced by the electromagnetic pull of the coil 90 differs essentially for different positions of the armature.

To fix ideas I will take the case of a lamp, constructed in accordance with my invention, in which I employ a series regulating 95 solenoid only and a core having attached to it a clutch, which core I here assume is sucked upwardly to strike the arc. I thereupon so construct my lamp that it shall require considerably more current to hold the 100 core in position when the core is in its highest position, that is after the arc has just been struck, than is required after the lamp has been burning and the core has gradually sunk down away from this highest position. I so 105 construct the lamp that the amount of current required to hold the core in position shall grow essentially less and less, as the core

moves down and down away from its highest position.

We are now in a position to see what will happen if we use say three lamps, 1, 2 and 3, each made in accordance with my invention, in series, on a circuit having an approximately constant potential impressed on its terminals. Consider the lamps after they have been burning for a short time and suppose that lamp 2 has an arc-length about half-way between the arc-lengths of lamps 1 and 3. The resistance of these arcs, taken in connection with the impressed voltage, will determine a certain current-flow. This current flow will manifestly correspond to the core-position of lamp 2. The core of lamp 1, which we will assume to have the longer arc, will however be higher up, or in a position nearer to that which it occupied when the arc was first struck. It will therefore require more current to hold it in equilibrium than that which is flowing. In consequence, the core of lamp 1 will exercise an unbalanced downward pressure sufficient to throw it into the relative position of the core in lamp 2, with such margin of error as I may initially determine. The core in lamp 3, which has the shortest arc, will be in a position below that of the core in lamp 2. In this position a less current than that which is actually flowing would hold it in equilibrium. This means that there is an unbalanced upward electromagnetic pull which, in accordance with my invention, I make sufficient to raise the core in lamp 3 to about the position of the core in lamp 2. It will thus be seen why I designedly construct the lamps so that a different equilibrating current corresponds to each different core position, and so that the differential pulls exercised by these different currents on the cores shall be sufficient to bring back to its position a core which is out of its position by a distance larger than a given permissible minimum.

As I have indicated above, my invention is naturally applicable not only to a lamp in which the armature or core is sucked upwardly but also to one in which it is sucked downwardly by the solenoid or electromagnetic coil. What is more I may construct a lamp embodying my invention and having the function here pointed out, in a variety of ways and by means of a variety of devices, either electrical or mechanical. I shall however merely show one embodiment of my invention emphasizing that my invention is not limited to the mere mechanical construction which I proceed to show, but resides more generally in a group of lamps on a constant potential circuit each lamp having the characteristic which I have now so fully pointed out.

In the drawings, — Figure 1 is a side elevation, partly in section, showing a lamp embodying my invention after the arc has just

been struck; Fig. 2 is a similar view showing the parts after the lamp has been burning for some time; and Fig. 3 is a diagrammatic view of three of these lamps in series across constant potential mains.

In the drawings I have shown my lamp with a series regulating coil 5 only. There is no shunt coil. The core 1 has pivoted to it a clutch 6 which embraces a carbon 7 so that as the core is pulled up in the solenoid, the clutch tilts and grips the carbon 7 and raises it to strike the arc. Fastened to the lamp frame is a pivot 50 upon which I mount a lever 2 connected, at one end, to the core 1 by a link 8 and, at the other end, to a dash pot 9 for the purpose of steadyng the movement. Rigidly connected with the lever 2 is an arm 3, at right angles to the lever 2, carrying a weight 4, the arm and weight constituting a bob.

It will be seen that when the core 1 is in its highest position, after the arc has just been struck, the bob is to the right of the center and exercises a force tending to depress the core. In effect the core is made heavier by the bob in its highest position. When the bob is vertical, it exercises no force upon the lever 2 and the core 1 exercises a downward pull determined by its weight and that of its attached parts. When the core is in its lower positions and the bob is to the left of the vertical, as in Fig. 2, it exercises a pressure tending to raise the core. This, in effect, makes the downward pull of the core less than that corresponding to its weight and that of its attached parts. In other words the action of the bob, within the limits of the travel of the core, is to make the core heavier the higher up it is drawn and lighter the lower down it falls. This means that the higher the core position, the stronger the current in the solenoid necessary to hold the core in that position. For every position of the core there is a corresponding but different equilibrating strength of current; the stronger currents corresponding to the upper core positions. More specifically stated, the downward mechanical pull of the core which has to be balanced by the upward electromagnetic pull of the coil differs essentially for different positions of the core. As a result, if the core is not in the position which corresponds to the current which is actually flowing, a differential force will be called into play, either in the shape of unbalanced mechanical downward pressure of the core or of unbalanced electromagnetic upward pull of the solenoid and, in my invention, this differential force is made great enough to bring the core to its position of equilibrium. A moment's consideration, however, will show that when my invention is embodied by adding a bob to the lamp construction, it is not necessary for this bob, during the travel of the core, to be first at one side and then at

the other side of the vertical. The bob may readily stay at one side of the vertical throughout the travel of the core, for even in this condition the parts can be so arranged as to execute what I may term the root-function of the lamp, namely to require a stronger and yet stronger current to hold the armature or core in position, the nearer this is to the position just after striking the arc, the differences in these current strengths being sufficient to call into play the differential restoring force, upon the lamp out of position, to which I have so frequently referred. Nor need I repeat that my invention is not limited to the mechanical device which I have shown for obtaining the function which I have set forth or to have the current grow gradually stronger since the lamp may be arranged to have the current grow gradually weaker.

It is clear that in one of its broader aspects the bob which I employ is a device which varies the mechanical pull exerted by the armature, or core itself, which pull must of course be balanced by the electromagnetic pull of the solenoid. I may therefore, for convenience, use the phrase mechanical pull-varying device to include all devices which act to vary the mechanical pull of the armature in its different positions. And when I speak of varying the pull, I mean of course that the variation of pull for the different positions shall be sufficient to bring into play the differential restoring force upon that armature which happens to be out of position.

For the purpose of insuring additional reliability in synchronism, I prefer to employ a regulation-restarter, which I proceed to describe. The lever 2 is extended to the left in a prolongation 10, carrying a pin 15, working in a slotted link 16, attached to the keeper 13, of an electromagnet 14, in the lamp circuit. The slot in the link is of sufficient length for a certain amount of regulation of the arc by means of the regulating solenoid 5, to take place, without any movement of the keeper, the pin 15 playing between the extremities of the slot 16 during such regulation.

Let us assume that the parts are in the position which they occupy when no current is on, that is to say with the carbons together, the clutches resting on their stops, the lever 2 lying inclined with the core well below the solenoid and the keeper hanging above the electromagnet with the pin at the top of the slot. When the current is now switched on, it traverses the pair of carbons, the solenoid 5 and the electromagnet 14. The core is pulled upwards, its end of the rocking lever is raised, the clutch is pulled up and the arc is struck. At the same time the other end of the rocking lever is depressed, the keeper 13 is brought within pulling distance of the electromagnet 14 and

is attracted and held by the latter. The distance through which the keeper moves is however smaller than the distance through which the pin on the rocking lever moves, so that the pin descends some distance in the slot and the keeper no longer hangs from its limb of the lever.

The usual arc-regulating action now takes place and the core drops gradually lower and the pin 15 rises in the slot 16. The keeper is however still held by the electromagnet and the action goes on until the pin has reached the head of the slot when the core can drop no further but remains stationary. The carbon cannot now feed and the arc gets longer until it breaks. The solenoid and electromagnet are now no longer traversed by the current, so that both core and keeper are released, the former dropping and bringing the clutch in contact with the stop so that the upper carbon drops into contact with the lower carbon. The circuit is now re-established and the cycle of operations takes place as before.

It will be seen that so long as the parts are in such positions that the pin is free within the slot a certain amount of regulation may take place, but that the carbons cannot be released so as to come in contact until the keeper is released from its electromagnet.

The process disclosed herein is claimed in my co-pending application Serial No. 411,679, filed January 20, 1908, as a division hereof.

I claim,

1. A constant-potential series circuit including arc-lamps, each comprising a series regulating coil only, and a coacting armature equilibrated in its several positions by current strengths which differ sufficiently in value that a differential restoring force is exerted upon any armature of the series which may be out of position, substantially as described.

2. A constant-potential series circuit including arc-lamps, each comprising a series regulating coil only, and a coacting armature exerting a variable mechanical pull differing sufficiently in its several positions to generate a differential restoring force upon any armature of the group which may be out of position, substantially as described.

3. A constant-potential series circuit including arc-lamps, each comprising a series regulating coil only, a coacting armature, and a mechanical pull-varying device co-operating with the armature, whereby a differential restoring force is exerted upon any armature of the group which may be out of position, substantially as described.

4. A constant-potential series circuit including arc-lamps, each comprising a series regulating coil only, a coacting armature, and a pivoted bob co-operating with the armature for exercising a differential re-

100

105

110

115

120

storing force upon such armature of the group as happens to be out of position, substantially as described.

5. A constant-potential series circuit including arc-lamps, each comprising a series regulating coil only, a coaxing armature equilibrated in its several positions by current strengths which differ sufficiently in value that a differential restoring force is

10 exerted upon any armature of the series

which may be out of position, and a regulation-restarter, substantially as described.

In testimony whereof I have signed my name to this specification in the presence of two witnesses.

FRANK M. LEWIS.
